SUSPENSION MEANS FOR CARCASS-CUTTING
SAWS

Ezekiel C. Steiner, 1438 E. Slausen Ave.,
Los Angeles, Calif. 90011
Filed June 30, 1965, Ser. No. 468,238
2 Claims. (Cl. 248—17)

This invention relates to suspension means for carcass-cutting saws and similar power tools that require to have their balance changed to facilitate the different angular cutting strokes required to be performed. If not all, most carcass-splitters provide two or more holes to which the end of a suspension cable may be selectively connected. One such hole is used when the tool is best presented for slitting a carcass at an upward angle, as when starting a slitting operation from the top of a carcass. Another is used in slitting performed with a more or less horizontal stroke. A third is used if the stroke is in a downward direction.

It will be realized that these tools weight between one and two hundred pounds, depending on whether they are to be used for splitting beef, veal or hogs, and that a well-balanced tool facilitates splitting operations and enables efficient and non-tiring work, as well as speeding the operation, obtaining cleaner, more accurate cuts, and generally lowering the cost of this type of work.

The above-mentioned known manner of providing for change of balance cannot, ordinarily, be carried out by the tool operator, alone. Changing the connection of the suspension cable from one hole to another usually requires the time and services of two men with resultant loss of operating time and ensuing increase in costs.

Recognizing the above-enumerated faults of known suspension means, an object of the present invention is to provide simple and improved suspension means for carcass-cutting saws and similar tools that enables the operator, by mere manipulation of the tool handle, to shift the point from which the tool is suspended relative to the unevenly distributed weight of such tools to obtain the desired balance or imbalance, as the case may be, thereby enabling tilting the tool at various up or down angles for best cutting results.

Another object of the invention is to provide a tool, as above characterized, in which the point of suspension floats or is freely movable in the shifting bight of a flexible hanger that is located at the center of gravity or balance of the tool.

Another object of the invention is to provide means for locking the point of suspension, thereby fixing the point of connection to the hanger.

The invention also has for its objects to provide suspension means comprising novel details and novel combinations of parts, which will become more clearly evident from the following detailed description of an exemplary form of the invention.

The above objects are realized in a construction in which a carcass splitter or like tool, at the upper part thereof at the center of gravity or balance, is provided with a length of chain with its ends longitudinally spaced and secured to the tool, the space between said chain ends being shorter than the length of the chain which, when extended, forms a bight. A free-turning sprocket pinion is engaged with the chain from beneath, and a yoke with a cross pin on which said pinion is mounted between the arms thereof has an upper hook that has a hanging connection with a hanger cable. The weight of the tool, when thus hung by the bight in the chain from said pinion-provided yoke, is ordinarily balanced to a general horizontal position. In this condition, the bight in the chain is approximately spaced the same from the points

2

where the chain ends are secured. This balance may be changed to cause the saw to assume an angular position, either up or down, by shifting the bight nearer one anchor point of the chain than the other. This may be accomplished by pulling rearwardly on the tool, pushing forwardly thereof, raising the handle end, depressing said end, or any combination of these movements. The end of the tool toward which the bight is moved will become over-balanced and that end will assume an upward angle. A lock for the pinion to prevent its rotation retains the same in a fixed bight to retain the balance or a pre-set imbalance of the tool.

In the drawing, in which like numerals designate similar parts:

FIG. 1 is a side elevational view of a carcass-cutting saw provided with the suspension means of the present invention and shown in normal balance position.

FIGS. 2 and 3 are enlarged and fragmentary vertical sectional views as taken on the respective lines 2—2 and 3—3 of FIG. 1.

FIG. 4, to a somewhat smaller scale than FIG. 2, is a vertical sectional view as taken on the plane of the line 4—4 of FIG. 2, the suspension means being shown in a shifted position and the tool angularly tilted accordingly.

The tool shown in FIG. 1 is representative of carcass-splitting saws. The same has a grip handle 5 at one end, a main body 6 forward of said handle, an electric motor 7 mounted on said body 6 and extending laterally therefrom, and a yoke 8 extending forwardly from the upper part of the body 6 and then downwardly at 9 to form a support arm for a cutter blade 10 then extends from said body 6 and is reciprocated by means driven by the motor 7 and housed in said body portion 6.

Such a tool is substantially heavier at the handle end than at the opposite end, due to the weight of the motor 7 and the mechanism connecting the same and the blade 10. This arrangement being typical of such tools, the one illustrated should be considered as exemplary and, per se, forms no part of the present invention.

Tools such as the one illustrated have, in the past, been provided with a hanger bracket extending fixedly upwardly from the body 6 at the center of gravity or balance of the tool. A series of holes, horizontally aligned, is provided in said bracket, a yoke hanging from a suspension cable being connected to a bolt in one of said holes, according to the angle of balance desired for the tool.

According to the invention, the present suspension means 15 comprises, generally, a length of chain 16, bicycle chain being preferred, two similar chain end anchors 17 at the upper part of the body 6 spaced on opposite sides of the center of gravity or balance 18 of the tool and a distance substantially less than the effective length of the chain 16, a sprocket pinion 19 engaged with the chain in a bight 20 formed therein by the weight of the tool, a yoke 21 mounting said pinion 19 and connected to a hanger cable 22, and means 23 to fix or lock the pinion 19 against rotation.

Each chain anchor is shown housed in a recess 25 in the body 6, the same comprising a block 26 fitted in said recess and having a seat 27 therein of U-form and in which the three links at the end of the chain may be fitted and retained against displacement by a bolt 28 extending through the block 26 and a plate 29 that closes the inner side of the recess 25, and threadedly engaged with the body 6. The head of said bolt holds the block 26 in place.

The length of the chain over the six links wrapped around the bolts 28, is sufficiently greater than the distance between the bolts so that the slack in said chain forms a flexible hanger loop. The sprocket pinion 19 is engaged from beneath with the links of said loop and is

free to turn with a cross pin 30 which is connected to the pinion by a key 31. Said pin has rotational bearing in aligned bores in the legs 32 of the yoke 21, has a polygonal head 33 at one end, and is retained in place by a lock nut 34. The legs 32 are connected by a loop 35. The mentioned cable 22 has its end wrapped around said loop with a clip or clips fixedly connecting the cable end for permanent connection with the yoke 15.

FIG. 1 shows the yoke 15 positioned midway between the anchors 17 when the pinion 19 forming and engaged in the bight 20 is midway between said anchors with equal runs 36 between the bight and the anchors. When the tool is shifted from a horizontal position to an angular position, or is pulled rearwardly or pushed forwardly, the pinion 19 will turn on the axis of pin 30 and the bight 20 will move nearer one of the anchors 17. FIG. 4 shows one such shifted position of the pinion with the bight 20 shifted to form a longer run extending to one anchor and a shorter run 38 extending to the other anchor. The tool, therefore, naturally assumes an angle to the horizontal and is in substantial balance at that angle. The difference in run lengths is increased as the angle steepens. The angle may, of course, be opposite to the one shown.

The chain 16 may be formed endless with the same trained over bolts 28 to form a straight run between said bolts and the loop as shown. The bolts, thereby, form anchors from which the loop extends in the manner described and from which the tool is suspended.

The yoke 15 may be locked to any part of the chain loop by locking the pinion against rotation. To this end, the means 23 is provided, the same being shown as a set screw 39 threadedly engaged in an ear 40 on one of the legs 32 and directed to engage a face of the pin head 34. FIG. 1 shows the pin locked and FIG. 2 shows the pin released, the operator having the choice according to the types of cut he is to make.

Since the foregoing is given by way of example, it is to be understood that the construction is subject to modification without departing from the spirit and scope of the appended claims. Therefore, I desire to reserve to myself all such modifications.

Having thus described the invention, what is claimed and desired to be secured by Letters Patent is:

1. Suspension means comprising:

- (a) a carcass splitter or the like having a body,
- (b) two longitudinally spaced anchor units provided on said body, each anchor unit comprising a block secured by a bolt to the splitter body and having a recess therein between the walls of which and the bolt, the mentioned end links of the chain are non-removably confined,
- (c) a length of bicycle chain having its end links anchored in said units, the length of the chain between said end links being substantially greater than the space between the anchored links at both ends, thereby forming a flexible loop comprising chain links,
- (d) a sprocket pinion having its teeth engaged with the loop links from beneath, said chain loop forming a bight around the pinion due to the weight of the splitter on the pinion, and
- (e) a cable-hung yoke having means for rotationally mounting said pinion for rolling engagement with the links of said chain.

2. Suspension means according to claim 1 in which

- (a) the yoke is provided with parallel arms between which the pinion is located,
- (b) the pinion-mounting means including a rotational pin extending between the arms and keyed to the pinion,
- (c) a polygonal head on said pin, and
- (d) a set screw carried by one of the arms and directed to engage a face of said head to retain the pin and pinion against rotation.
